METAL CONTAINER

Ronald Leroy Wakelee, Chicago, Ill., assignor to
Continental Can Company, Inc., New York,
N. Y., a corporation of New York

Application February 20, 1935, Serial No. 7,412

2 Claims. (Cl. 220—27)

The invention relates to new and useful improvements in a metal container of the friction closure type, and more particularly to a container wherein a frangible sealing member is used in conjunction with the friction closure.

An object of the invention is to provide a container wherein a frangible sealing member is disposed within the container beneath the friction closure and is secured by a clamping means formed in part by a shaping of the body wall of the container and in part by a shaping of the container top.

A further object of the invention is to provide a metal container of the above type wherein the body wall is bent inwardly to form a seating ledge, and the container top is shaped so as to form a pocket for a sealing material, and wherein said seating ledge and container top are so shaped and dimensioned as to clamp the peripheral edge portion of the sealing disk.

In the drawing—

Figure 1 is a view partly in side elevation and partly in section showing a container embodying the improvements;

Fig. 2 is an enlarged sectional view of the upper portion of the container at one side thereof, and Fig. 3 is a view similar to Fig. 2, but showing a modified form of container top.

The invention relates particularly to a metal container of the friction closure type having a frangible sealing member used in conjunction therewith. The container comprises a body portion of metal having ends double seamed thereto. The body wall of the container is beaded inwardly and the inwardly projecting bead is shaped so as to form a seating ledge against which a frangible sealing disk may be clamped. This seating ledge is disposed a slight distance below the double seam joining the container top to the body of the container. The container top is provided with an opening which is surrounded by a vertical friction wall adapted to receive a friction plug closure. The container top adjacent the opening is shaped so as to provide a rounded shoulder, and between said rounded shoulder and the seam joining the container top to the body of the container is a pocket for a sealing material. A frangible sealing disk extends across the opening and contacts with the rounded shoulder and terminates in said pocket. The seating ledge and the pocket in the container top are so disposed and dimensioned that when the container top is placed on the container body preparatory to seaming the same thereto, the peripheral edge

portion of the frangible sealing disk will be firmly clamped in the pocket and against the sealing material therein.

Referring more in detail to the drawing, the container includes a body portion 1 to which a lower end 2 is secured by a double seam 3. The container top 4 is secured to the upper end of the body wall 1 by a double seam 5. The body wall of the container is bent inwardly to form a bead which is brought together and slightly bent upward at the inner edge so as to provide a seating ledge indicated at 6 in the drawing.

As shown in Figures 1 and 2, the container top 4 is provided with a central opening surrounded by a vertical friction wall 7. Said vertical friction wall is rolled outwardly into a hollow bead 8 at its upper end. This container top is formed from a single blank of metal which is drawn to give the desired shape to said top. Adjacent the lower edge portion of the vertical friction wall there is a rounded shoulder 9. Between this rounded shoulder 9 and the double seam 5, the container top curves upwardly at 10, and is thus shaped to provide a pocket for a sealing material 11.

Extending across the opening at the lower end of the vertical friction wall 7 is a frangible sealing disk 12, preferably of aluminum. This sealing disk may be made, however, of tagger's tin, paper, or any other material which may be readily ruptured. The sealing disk is dimensioned so that it rests against the rounded shoulder 9 and extends into and terminates in the pocket containing the sealing material 11. The seating ledge 6 and the container top are shaped and dimensioned so that when the container top is placed on the container body preparatory to the seaming of the same to the container body, the peripheral edge portion of the sealing disk will be clamped between the container top and the seating ledge 6, and firmly pressed against the sealing material 11 in the pocket. This forms a very firm securing means for the frangible sealing disk and also an hermetic or airtight joint between the sealing disk and the container top.

The friction plug closure 13 is provided, which closure has a vertical friction wall 14 adapted to engage the vertical friction wall 7 on the container top. At the upper edge of the closure 13 there is a laterally projecting flange 15 which is curled downwardly and inwardly as indicated at 16.

The container top is shaped for attachment to the container body, and a sealing material is applied to the pocket therein, after which the

frangible sealing disk is laid across the opening, contacting with the rounded shoulder, and the container top and sealing disk are then attached to the container body and the double seam formed for joining the container top to the container body. This is all done by the manufacturer of the container. The packer, before the container end 2 forming the bottom is attached thereto, inverts the container and places 10 in the container the product which is to be packed therein, after which the container end 2 is secured to the container body by double seaming. The friction closure plug is inserted by the manufacturer and serves to protect the 15 frangible sealing disk. When it is desired to open the container, the friction closure is removed and a sharp instrument is used for rupturing the disk at the inner edge of the rounded shoulder 9. The friction closure can be 20 inserted for closing the container after the ruptured portion of the sealing disk is removed. If the customer finds the sealing disk ruptured when the package is purchased, it is an indication that the container has been opened and the contents 25 tampered therewith. Not only is the sealing disk used for preventing tampering with the contents of the container, but it also forms an airtight seal for the container which is difficult to obtain between the two friction walls of the friction closure and the container top.

In Fig. 3 of the drawing, there is shown a slightly modified form of container top. In this form of the invention, the container top 4 is provided with a vertical friction wall 17 which 30 is spaced close to the body wall of the container. The body wall 1 of the container is shaped to form the seating ledge 6 such as described in connection with the container shown in Figures 1 and 2. The container top has an opening 18 which is spaced away from the wall 17, and the metal of the container top is folded back underneath the container top, as indicated at 19. This provides a rounded shoulder 20. Between the opening 18 and the vertical friction wall 17 the container top is curved upwardly as indicated at 21. This provides a pocket for a 40 sealing material 22. Extending across the opening 18 is a frangible sealing disk 23 which contacts with the rounded shoulder 20 and extends into the pocket so that the peripheral edge portion of the frangible sealing disk may be brought into engagement with the sealing material 22. The container top and the seating ledge are 45 shaped and dimensioned so that when the container top is in place for securing by the double seam to the container body, the frangible sealing disk will be drawn tight against the rounded shoulder and clamped firmly between the seating ledge and the sealing material 22 in the pocket. The frangible sealing disk will also be 50 clamped between the folded back portion of the metal of the container top and the inner edge of the seating ledge. This provides a very firm clamping for the frangible sealing disk and also 55 a holding means which forms an airtight seal between the disk and the container top. An outer friction closure 24 is provided, which closure has a vertical friction wall 25 adapted to 60 contact with the vertical friction wall 17. Said

closure 24 is rolled outwardly to form a hollow bead 26 which is adapted to contact with the extreme upper portion of the double seam 5. It will be noted that the wall 17 of the container top is spaced away from the wall 1 of the body 5 of the container so that it may yield to receive the friction closure 24. When it is desired to open the container, the friction closure 24 may be pried out and the frangible sealing disk readily ruptured at the inner edge of the rounded shoulder 20.

From the above it will be apparent that a metal container has been provided wherein the frangible sealing disk is secured by a shaping of the body wall and the container top which 15 is independent of the double seam, so that the attachment of the sealing disk to the body wall does not, in any way, interfere with the formation of the double seam.

It is obvious that many changes may be made 20 in the details of construction without departing from the spirit of the invention as set forth in the appended claims.

Having thus described the invention, what I claim as new and desire to secure by Letters 25 Patent, is—

1. A metal container comprising a body portion having the wall thereof bent inwardly to provide a seating ledge for a frangible sealing disk, a container top secured to said body above 30 said seating ledge by seaming, said container top having an opening therethrough surrounded by a vertical upstanding friction wall, a closure member adapted to frictionally engage said upstanding wall for closing said container, said container top being shaped so as to provide a rounded shoulder adjacent the lower end of said opening therein, and a pocket for the sealing material between said rounded shoulder and said seam, and a frangible sealing disk extending 35 across said opening contacting with said rounded shoulder and terminating in said pocket, said seating ledge and said container top in the region of the pocket being shaped so as to cooperate in the clamping of the peripheral edge 40 portion of the sealing disk for forming a tight seal between the sealing disk and the container top.

2. A metal container comprising a body portion having the wall thereof bent inwardly to form 50 a seating ledge for a frangible sealing disk, a container top seamed to said body portion above said seating ledge, said container top having an opening therethrough surrounded by a vertically extending friction wall, a friction plug closure 55 adapted to engage said friction wall on the container top for closing said container, said container top having a portion thereof between said opening and said seam shaped so as to provide a rounded shoulder adjacent the opening and 60 a pocket for a sealing material between said rounded shoulder and the seam, a sealing disk extending across said opening contacting with said rounded shoulder and terminating in said pocket, said pocket and said seating ledge being 65 disposed and dimensioned so as to grip said peripheral edge portion to form a tight seal.

RONALD LEROY WAKELEE.
